UNITED STATES PATENT OFFICE

142,720

DESIGN FOR A REVERSIBLE PICTURE FRAME OR THE LIKE

Edmund D. Kissling, New York, N. Y.

Application July 4, 1945, Serial No. 120,524

Term of patent 7 years

(Cl. D29—20)

To all whom it may concern:

Be it known that I, Edmund D. Kissling, a citizen of the United States of America, residing at New York, in the county of New York and State of New York, have invented a new, original, and ornamental Design for a Reversible Picture Frame or the like, of which the following is a specification, references being made to the accompanying drawing, forming a part thereof, in which versible picture frame showing my new design in self-supporting position.

Figure 2 is a side elevational view thereof, and Figure 3 is a side view of the frame reversed and in the position assumed when hung on a wall support.

I claim:

The ornamental design for a reversible picture frame or the like, as shown and described.

EDMUND D. KISSLING.
